1

The present invention relates to a method and apparatus for gripping and cutting off the inactive threads in straight sinker operated knitting frames and similar machines, in which the said threads are automatically pulled out to form a loop between the mouth of the tube of the thread guide or guides and the point of introduction into the product.

The method hitherto known for clamping and cutting off the inactive threads in straight sinker operated knitting machines consists in introducing one of the folds of the V-shaped loop, which is formed automatically between the thread guide and the product, into a clamping device and the other fold into a cutting device, which is separately located and driven. This method has the disadvantage that the respective clamping device is not fully reliable so that the inactive threads are not held with complete safety. Some of the insufficiently retained inactive threads may be incidentally pulled out of the clamping device at an inopportune moment, such as when introducing a fresh thread into the work, so that the corresponding thread guide does not possess a thread when it is put in operation, which defect is encountered in many cases. Moreover, by cutting off the second fold of the loop, two free relatively long thread ends are obtained of which that one which is hanging down from the clamping device must be drawn gradually and during a relatively long period from the clamping device by the product which increases in length. Another disadvantage of the apparatus referred to resides in its relative complexity as to arrangement and control. The retaining hooks and the clamping and cutting-off devices are driven by a separate shaft, laterally slideable and rotatable, which is operated in some cases for a time by a hand actuated control rod.

The same method of clamping and cutting off the inactive threads is employed also in the so-called heel machines where on each side of the needle bank there are arranged two superposed movable hooks which are guided in longitudinal grooves in the direction of the length of the machine. The disadvantage of this method consists in the necessity of opening the clamping device to release the clamped severed fold of the loop at the beginning of the knitting operation with a freshly introduced thread guide. Another disadvantage of the apparatus consists in this that it may be used only for machines having a small number of thread guides, for instance for heel machines, and not for cotton machines having from eight up to ten thread guides.

2

A purpose of the present invention is to eliminate the above quoted imperfections so as to achieve complete safety in the operation, obtain a single free fold of the loop, secure a more suitable arrangement and simplify the whole apparatus together with its drive.

The main feature of the new method consists in cutting off the inactive threads clamped by the clamping device at a point close to the said device. The advantage of the method just outlined consists in this that the cut off fold of the loop clamped in the clamping device has no free end and therefore may be pulled out quickly from the clamping device by the movement of the product as it increases in length.

Another improvement in accordance with the new method consists in an arrangement in which during the period of pulling out the threads to form loops by means of one or more retaining hooks, the clamping and the cutting-off devices are moving in the direction of movement of the sinkers of the machine toward the loop or loops being formed. In this way the fold of the loop between the retaining hook and the thread guide is brought quite reliably between the jaws of the clamping device. The clamping device by its working stroke into the direction of movement of the sinkers of the machine, causes the device for introducing the inactive threads in the clamping and cutting-off devices to be operated, while by its return stroke to inactive position causes the said device to be put again out of operation. The arrangement just described achieves a perfect introduction of the inactive thread into the clamping device, and no particular drive is required for this purpose.

The clamping device forms a part of the cutting-off device in that one of the jaws of the clamping device has a knife edge which co-operates with the edge of a knife mounted rotatably on the said jaw. The knife, which partakes of the movement of the clamping device in the direction of movement of the sinkers of the machine toward the loop being formed, is controlled at the same time by a rockable cam member. In this arrangement no separate drive for the cutting-off device is required.

According to another feature of the present invention, all the retaining hooks located on both sides of the sinker heads and their directly associated clamping, cutting-off and introducing devices for the threads are brought to working position and out of the same by means of bars slideable in the longitudinal direction of the machine. This arrangement on both sides of the

sinker heads has a great advantage in that the V-shaped loops under formation are kept as short as possible and the narrowing needles can operate safely. The movements of all the retaining hooks are controlled by two bars reaching from side to side of the machine, and the movements of all the clamping, cutting-off and introducing devices are controlled in common by a single bar. With either of the two bars those retaining hooks are moved which are located on one and the same side of the needle bank. The drive of the superposed bars is effected by a centrally located control member, comprising a cylindrical cam.

A still further feature of the present invention consists in the arrangement of a coupling which permits a single rotation of the cylindrical cam just referred to and which, after reaching the end position of the thread guides on one or the other side of the needle bank, is thrown in or out automatically by means of a lever system from a pattern drum or pattern chain.

An embodiment of the invention will be described in greater detail in the following description with reference to the accompanying drawings, in which

Fig. 1 is a side elevation of the drive of the apparatus for carrying out the method in accordance with the present invention on a straight sinker operated knitting machine, which is shown in part only;

Fig. 2 is a section along the line 2—2 of Fig. 1 through the one revolution coupling;

Fig. 3 is a front elevation showing a part of the arrangement of the apparatus and of its drive on a straight sinker operated knitting machine;

Fig. 4 is a partial plan corresponding to Fig. 3 and showing the arrangement of the clamping, cutting-off and introducing devices adjacent to the sinker heads;

Fig. 5 is a view showing the apparatus arranged adjacent to a sinker head on the right hand side of the needle bank in a position for cutting off the pulled out inactive thread;

Fig. 6 is a detail view showing the drive of the introducing device for inactive threads;

Fig. 7 is a detail view showing the knife immediately after the thread has been cut off in co-operation with a rockably mounted cam member and with the jaws as viewed in the direction of the arrow P in Fig. 5;

Fig. 8 is a partial view showing the arrangement of the retaining hooks on the bars of the knitting machine;

Fig. 9 is a view showing the drive of the bars by the cylindrical cam; and

Figs. 10 to 14 show diagrammatically the various phases of the operation of the retaining hook, clamping device and introducing device from the moment of gripping an inactive thread up to the moment of cutting off the same.

Fig. 1 shows a part of the left hand side frame member 1 of a standard straight knitting machine having a transverse carrier 2, a bar 3 reaching from side to side of the machine, and a working table 4; these elements connect together the two side members of the machine. The side members carry a main cam shaft 5, and the transverse carrier supports the sinker heads 6, Fig. 4. Of the standard knitting devices of the machine only the sinkers 7 and needles 8 are shown. Within the range of each needle bank, a clamping device is fastened on the carrier 2 laterally of each sinker head 6, the clamping de-

vice carrying the devices for pulling out, introducing and cutting off the threads.

The clamping device consists of a bracket 9, Fig. 3, screwed to the carrier 2, and a body 10, Fig. 5, slidably in the bracket 9 and formed with a lower clamping jaw 11 having a knife edge 12, Fig. 7. The under surface of a cover plate 13, Fig. 5, connected by means of screws with the bracket 9, serves as a guide surface for the body 10. The upper clamping jaw 14 is mounted rotatably on a pin 15 screwed into the body 10 and is constantly urged by a flat spring 16 against the lower clamping jaw 11 in such a way, that the inner horizontal faces of the jaws bear against each other. The pressure of the flat spring 16 on the jaw 14 may be adjusted. This possibility is of importance both for securing a perfect gripping of the inactive threads and for releasing those threads which have to be used in the knitting operation. The fixed end of the spring 16 is threaded on a guide bolt 17 screwed into the body 10, and is fastened by means of a nut 18. The guide bolt 17, projecting at right angles from the body 10, bears against a cam member 19 fastened on a holder 20 which is carried along with the bar 21. On the support 22 of a holder 23, Fig. 6, which support is fastened to the bracket 9 by means of screws, there is secured one end of a tension spring 24, the other end of which is threaded on a pin 25 held in the body 10.

The cutting-off device consists of a knife 26, Fig. 7, rotatably mounted on a pin 27 which is screwed into a lateral wall of the body 10. The knife 26 has a cutting edge 28 cooperating with the cutting edge 12 of the lower clamping jaw 11. In addition the knife 26 is provided with a cam pin 29 on which one end of a tension spring 30, Fig. 7, is hung, the other end of the spring being connected to a support 31, Fig. 5, which is fastened on the body 10. A pin 32 held in the body 10 serves as an abutment for the knife 26. The cam pin 29 of the knife 26 cooperates with a cam face 33 formed on the end of an arm 34 mounted rotatably on a pin 35 which is screwed into the bracket 9. The level of the arm 34 and thus the level of the cam face 33 relatively to the cam pin 29 of the knife 26 may be regulated by means of an adjusting screw 36 mounted in the bracket 9 and secured by a nut 37. A torsion spring 38 on a pin 39, on the bracket 9, urges the arm 34 together with the cam face 33 downwards against the adjusting screw 36.

The thread introducing device is operated by the clamping device. For this purpose the second side wall of the body 10 is provided with a cam groove 40, Figs. 5 and 6, in which engages the guide pin 41 of an arm 42 pivoted at one end on a pin 43 on the bracket 9. The other end of the arm 42 is provided with a supporting pin 44 which slides along one arm 45 of a bell-crank lever 46. The other arm 47 of the said lever 46 is bent in the direction towards the jaws 11 and 14 and is extended to form an enlarged extremity 48 which is provided with a notch 49 to permit reliable engagement with and introduction of the threads between the jaws which are in contact with each other. The bell-crank lever 46 is mounted rotatably on a pin 50 screwed into a holder 51 which is fastened on the transverse carrier 2 adjacent to the bracket 9. The arm 45 of the lever 46 is urged against the supporting pin 44 by means of a torsion spring 52 on a pin 53 provided on the holder 51.

The device for pulling out the inactive threads

consists of a holder 54, Fig. 5, screwed on the bracket 9. The holder 54 is provided with a guide bar 55 which is curved at one end and serves as a guideway. Short of the curved part of the guide 55 the free end of a flat spring 56 bears against the said guide, the other end of the spring being fastened to the holder 54. A lever 58, pivoted on pin 62 on a holder 63 mounted on bar 64, has one end 57 downturned to bear against the guide 55 and the other arm shaped to provide a thread retaining hook 59, and is urged in a direction to keep the end 57 in contact with the guide 55 by a torsion spring 60 carried by a pin 61 on the holder 63.

With this bar 64, which is located above the bar 21, are moved all those retaining hooks 59 which are located at the right hand side of the needle banks. The remaining retaining hooks, which serve to pull out the threads at the left hand side of the needle banks, are moved together with a bar 65 which is located above the two bars 21 and 64. The three driving bars 21, 64 and 65, Fig. 9, are mounted slidably in holders 66 which are screwed on the side members 1 of the machine. Each bar has screwed thereon a driving plate 67 with a longitudinal slot 68 in which a supporting pin 69 is guided. Each supporting pin 69 is arranged at one end of a lever 70, the levers being mounted for rocking movement about pins 71, screwed into a bracket 72. The other end of each lever 70 carries a roller 73 engaging in a corresponding groove 74 of a drum 75 which is keyed on a shaft 76. The number of grooves 74 corresponds to the number of bars. The shaft 76 is mounted in brackets 77 and 78 which are fastened by means of screws on the bracket 72 carried by the bar 3, Fig. 1. On one end of the shaft 76, Fig. 9, is keyed a hand wheel 79 serving to rotate the cylindrical cam 75 by hand and to adjust the cutting-off device. On one of the end faces of the cam 75 there is screwed a circular disk 80 provided with a single recess 86 for a pawl, Fig. 1. The corresponding pawl 81 is mounted on a pin 82 screwed into the face of a sprocket wheel 83 which is freely rotatable on the shaft 76. The pawl 81 is urged to engage with the recess 86 in the disk 80 by means of a torsion spring 84 mounted on a pin 85 which is carried by the sprocket wheel 83.

Angular movement of the cylindrical cam 75 to automatically pull out an inactive thread into a V-shaped loop, and the operation of the device for introducing one of the folds of the loop into the clamping and the cutting-off device are carried out by means of a one revolution coupling which after being released by means of a lever system from the pattern drum is driven by the main cam shaft 5. In order to secure reliable operation of all the clamping and cutting-off devices in the machine and to prevent the inactive threads from breaking, the working process from the moment when the threads are pulled out up to the moment of cutting off the same is divided into two parts corresponding to two revolutions of the main cam shaft 5 or to one angular movement of the drum 75. During a revolution of the cam shaft, the pulling hook will pull out an inactive thread into a V-shaped loop, while during the second revolution it will introduce the thread into a clamping and cutting device.

The chain 87, Figs. 1 and 3, which runs around the sprocket wheel 83, is guided over a sprocket wheel 88 having an extended hub portion 89, Fig. 2, freely rotatable about a pin 90 fastened in

the side member 1 and clamped by means of a nut 91. On a shouldered washer 92 freely rotatable on the hub 89 there is sprung from one side a rocking sector 93 whose circular periphery 5 of larger diameter is provided at one point with a notch 94, Fig. 1, for a locking pin 95 which retains the sector 93 in inoperative position. In the lateral wall of the sector 93 there is screwed a pin 96 on which a pawl 97 is rotatably mounted. 10 The driving sector 93 carries a plate 98 in which an adjusting screw 99 is screwed in such a manner as to cooperate with an abutment 100 provided on the wall of the side member 1. A tension spring 103 is connected to an ear 101 fastened 15 on the plate 98 and to a post 102 screwed into the side member 1. The end of the hub 89 has keyed thereon a gear wheel 104 which has a number of teeth omitted on its periphery so that a gap 105 without teeth is formed. The gear wheel 104 is 20 rigidly connected to a circular disc 106 which is provided with a recess 110 and against the periphery of which bears the end of the pawl 97 urged by a torsional spring 107 fastened on a pin 108 which is provided on the sector 93. 25 The relative position of the sector 93 and disc 106, and of the gear wheel 104 as well, is secured in the idle condition by means of an arresting pin 111 engaging in a recess 109 in the circular periphery of the sector 93 of smaller diameter, 30 Fig. 2, and in the recess 110 of the disc 106, the said pin 111 being urged by a spring 112 housed in a bracket 113 which is fastened to the side member 1 by means of screws. With the gear wheel 104 is associated a pinion 114 having one 35 half of the number of teeth of the said gear wheel and adapted to co-operate for a time with the latter. The pinion 114 is keyed on one end of a shouldered shaft 115 mounted rotatably in the side member 1. To the end of the shaft 115, 40 adjacent to the pinion 114, there is fastened a lever 116 adjustable by means of a clamping screw 117 in such a manner that a driving pin 118, fastened in the opposite end of the lever 116, is adapted to co-operate for a time with 45 the driving sector 93. The other end of the shouldered shaft 115 has keyed thereon a sprocket wheel 119, Fig. 1, which is continuously driven by means of a chain 120 from a sprocket wheel 121 fastened on the main cam shaft 5. 50 An impulse for effecting angular movement of the one revolution coupling is given at the right moment by a pattern drum 122 which is mounted rotatably in the left side member 1 and is provided around its periphery with a number 55 of projections of various height and length, from which for instance the projection 123 co-operates with a lever 124 mounted for rocking movement about a pin 125. A link 126 pivoted on the lever 124 is connected at its other end with an 60 arm 127 which is fastened on one end of a shaft 128. This shaft 128 is mounted for free rotation in a bracket 129 fastened to a bar 130 by means of screws. A retaining ring 131, Fig. 3, prevents the shaft 128 from moving sidewise. 65 On the opposite end of the shaft there is fastened an arm 132, Fig. 1, which by means of a draw rod 133 is connected with one arm of lever 134 mounted rotatably about a pin 135 on the side member 1. The other arm of the lever 134 has screwed thereon a holder 136 and through 70 the end of this arm passes the locking pin 95 provided with a compression spring 137 which acts on the pin such a way that the end of the latter projects permanently from the lever 134 and by engagement in the notch 94 of the sector 75

93 locks the single revolution coupling in its inactive position.

The apparatus as described operates in the following manner:

During normal knitting, the main cam shaft 5, Fig. 1, drives continuously the sprocket wheels 121 and 119 which have the same number of teeth so that shaft 115, pinion 114, lever 116 and the driving pin 118 of the latter are continuously rotating, but without the rotating pinion 114 being in engagement with the gear wheel 104 because the gap 105 without teeth on the periphery of the gear wheel 104, Fig. 1, is positioned opposite to the pinion 114. This position of the gap 105 is determined by the driving sector 93 being held in its inactive position by engagement in its notch 94 of the locking pin 95 provided on the lever 134, which is held by the links 133 and 126 and by the levers 132 and 127, the end of the lever 124 occupying its idle position on the periphery of the pattern drum 122.

When the thread guides are changed on one or more needle banks, the one or more idle thread guides are positioned on the side of the sinker heads 6, Fig. 4, each idle thread of the needle bank being tensioned between the knitted product and the tube of the idle thread guide. If the machine is provided, with seven thread guides, three of the guides, for instance, may be put out of operation on the right side of the needle bank and four guides on the left side, or vice versa. Since the knitting operation is continued with the newly introduced thread guide, each section of the products would pull indefinitely with itself the idle thread extending between the product and the tube of the idle thread guide. For this reason it is necessary to make provision for clamping and cutting off at the same time the idle thread on the one or the other side of the needle bank, or needle banks, without affecting the inactive threads of the other idle thread guides held in the clamping devices.

The automatic pulling-out, clamping and cutting-off operations just referred to may be effected simultaneously with the arresting of the idle thread guides, or after the latter have reached their normal inactive position or in the proximity of this position.

An impulse for the operation of the apparatus in accordance with the invention is given by the pattern drum 122, Fig. 1, the step by step motion of which is derived from the main cam shaft 5, the projection 123 raising the end of the lever 124 and as a consequence the link 126 and the lever 127. After the first angular movement of the pattern drum 122, the end of the lever 124 lies on the projection 123. The rotation of the shaft 128 causes the lever 132 to rock so that the link 133 produces a rocking movement of the lever 134 and causes the locking pin 95 to be released from the corresponding notch 94 in the driving sector 93. Under the action of the tension spring 103 the sector 93 together with the washer 92 and the pawl 97 rotate on the extended hub 89, Fig. 2, in a clockwise direction as viewed in Fig. 1, into the path of the rotating driving pin 118 through such an angle until the end of the adjusting screw 99 comes to bear against the abutment 100. During this operation the pawl 97 slides on the face of the disc 106, which does not rotate for the time being, and in the recess of the disc without producing any displacement. By partial rotation of the driving sector 93 in the above mentioned direction, the

arresting pin 111, Fig. 2, is released from the recess 109 of the sector 93 and from the recess 110 of the disc 106 and is brought in contact with the circular periphery of the sector, compressing thereby the spring 112 in the bracket 113. The driving pin 118, which is moving along a circular path, strikes against a projection of the driving sector 93 and causes the latter to rotate in counterclockwise direction as viewed in Fig. 1. During this rotation the sector entrains with it the pawl 97 which under the action of the torsion spring 107 will engage in the recess 110 of the disc 106. As a consequence, this disc and the gear wheel 104 begin to rotate together in counterclockwise direction so that the rotating pinion 114 will come in engagement with the gear wheel 104 which then is rotated once about its axis. In view of the transmission ratio 1:2 between the gear wheels 104 and 114, Fig. 2, the driving pin 118 will then leave again the sector 93. The latter will begin to rotate again in clockwise direction under the effect of the spring 103 and will be pushed for the second time by the revolving driving pin in counterclockwise direction. During this period the sprocket wheels 88 and 83, Fig. 3, are rotated by the same number of teeth in counterclockwise direction as viewed in Fig. 1, and will perform one revolution about their axes. The sprocket wheel 83 carries with it also its pawl 81, Fig. 1, together with the disc 80 and the cylindrical cam 75. During a revolution of the gear wheel 104, disc 106, sprocket wheels 88 and 83 and cylindrical cam 75, all the grooves 74 cause the respective levers 70, Figs. 4 and 9, to rock at the same time or successively. The upper and the middle bars 65 and 64 are first operated in opposite directions and then at a latter stage the lower bar 21 is moved in the same direction as the upper bar 64. The retaining hooks 59 connected to the upper bar 65, Fig. 8, which normally are positioned at the left of the needle bank, are moving at the beginning of their paths along the needle row to the right and back again, while the retaining hooks 59 of the middle bar 64 which normally are positioned to the right of the needle bank, are moving at the same time to the left and then back again. Depending on the side of the needle bank at which one of the thread guides is arrested, either the right hand or the left hand retaining hooks 59 perform useful work, this work being effected on all the needle banks of the machine at the same time.

If the thread guide is arrested, for instance, at the right side of the needle bank, Fig. 4, so that its inactive thread extends between the guide tube and the right hand extreme sinker 7, the retaining hook 59 and its directly associated introducing, clamping and cutting-off devices located at the right hand side of the needle bank are in operation. The downturned end 57 of the lever 58, whose other end is formed as a retaining hook 59, bears during this stage against the deflected end of the guide 55. During the movement of the bar 64, and of the lever 58 carried with this bar, to the left the downturned end 57 of the said lever slides on the surface of the flat spring 56, Fig. 10, towards the inactive thread so as to locate the retaining hook 59 beyond the tube of the idle thread guide. In the left hand point of reversal of the path of bar 64 the bent end 57 of the lever 58 will slip, under the action of the torsional spring 60, from the end of the flat spring 56 secured to the holder 54 on to the straight leading end of the guide 55

so that the lever 58 will rock about its pin 62. The retaining hook 59 which is located behind the tube of the thread guide already before the said rocking movement, will grip reliably the inactive thread during the rocking of the lever 58. During the back movement of the bar 64 and of the lever 58 to the right the downturned end 57 of the lever 58 slides along the straight wall of the guide 55 and at the end of its straight path will raise the free end of the flat spring 56, the retaining hook 59 being thus caused to pull out the inactive thread into a V-shaped loop, Fig. 11.

At this moment the body 10 together with the closed jaws 14 and 11, the guide bolt 17 and the knife 26 begin to move toward the loop being formed as a result of the movement of the lower bar 21 with the holders 20 and the cam faces 19 longitudinally of the machine in the direction to the right. Due to the lateral displacement and to the pressure exerted by the cam face 19 on the upper part of the bolt 17 on the body 10, the pin 29 of the knife 26 will engage with the cam face 33 of the lever 34, the pin 29 being subjected to the action of the spring 30, whereby the knife 26 is raised or opened. Concurrently with the movement of the body 10 in a direction opposite to the loop being pulled out, the guide pin 41 of the arm 42 is lowered by the effect of the groove 40, and then the lever 42 by means of its supporting pin 44 exerts pressure against the arm 45 of the lever 46, Fig. 6. As a consequence the other arm 47 of the lever 46 will rock about its pin 58 in the direction towards the jaws 11 and 14, the notch 49 in the enlarged end 48 being brought in contact with the upper fold of the loop, causing this upper fold of the loop to enter between the closed jaws 11 and 14, Fig. 12. For an easy and reliable introduction of the said fold of the loop between the jaws, the moving downturned end 57 of the lever 58 will be brought, concurrently with the movement of the clamping and cutting-off device, in contact with the deflected part of the guide 55, so that the returning hook 59 which holds the loop and is moving away from the jaws 11 and 14, is caused to turn in the direction towards the guide 55. By the simultaneous movement of the pulling, clamping and introducing devices the upper fold of the loop is introduced and clamped in this way between the jaws 11 and 14 and beneath the raised knife 26. A short time before the loop is cut off and its upper fold is severed, the end of the bolt 17 is in a position close to the front straight surface of the cam member 19. The cam pin 29 of the knife 26 at this moment occupies a position at the end of the cam face 33 of the arm 34. In this stage the downturned end 57 of the lever 58 is at the end of the deflected part of the guide 55 and the enlarged end 48 of the bell-crank lever 46 is at the side of the body 10 behind the jaws 11 and 14. When the bolt 17 has reached the front face of the cam member 19, the cam pin 29 will slip from the cam face 33 under the action of the tension spring 30, and as a consequence the knife 26 will fall on the pin 32. The edge 28 of the knife 26 and the cutting edge 12 of the lower clamping jaw 11 will sever the clamped upper fold of the loop in the corresponding vertical plane of the body 10 close to the jaws while the lower fold of the loop is released, Figs. 5 and 13.

During the back movement of the bar 21 together with the cam members 19 to the left, the bolt 17 under the action of the tension spring 24 is moving along the inclined surface of the cam

member 19, whereby the body 10 together with the closed jaws 11, 14 and the loop fold clamped between the latter are returned to the original inactive position. During this back movement of the body 10, the arm 42 is raised due to the action of the groove 40 upon the guide pin 41, and under the action of the torsion spring 52 on the arm 45 of the bell crank lever 46 the other arm 47 of the lever is returned to its original inactive position. With the returning body 10, the pin 29 of the closed knife 26 will pass under the cam face 33 of the arm 34, Fig. 7, so that the latter is raised, but falls again under the action of the torsion spring 38. As soon as the bolt 17 has moved over the inclined surface of the cam member 19 and reached its starting position, the clamping device also has reached its idle position, in which one or more inactive threads are clamped and held by the jaws 11 and 14. At the same moment the gear wheel 104, Fig. 1, of the one revolution coupling has terminated its single revolution and interrupted for a time its engagement with the pinion 114 due to the gap 105 without teeth, the pinion 114 continuing to rotate without interruption. The sector 93, which is urged for a second time by the driving pin 118, Fig. 2, in counterclockwise direction, is locked in its idle position again by engagement of the arresting pin 111 in the recess 109 of this sector, the pin engaging also in the recess 110 of the disc 106, and also by the engagement at the proper moment of the locking pin 95 in the corresponding notch 94 on the circular periphery of larger diameter of the sector 93. An impulse for the engagement of the locking pin 95 is given again by the pattern drum 122 which performs another angular movement under the control of the main cam shaft 5. During this second angular movement, the end of the lever 124 slips down from the projection 123 so that the link 126 together with the lever 127 are moving toward the drum 122. Due to the partial rotation of the shaft 128, the lever 132 is caused to rock in such a way that the link 133 causes the lever 134 to rock and the locking pin 95 to be engaged.

The exchange of the thread guides and thus also the pulling, introducing, clamping and cutting-off operations for one or more threads on the one or the other end of a single or multiple needle bank machine are thereby terminated. Normal knitting will be resumed with the freshly introduced thread guide or guides. If one of the inactive threads held by a clamping device is to be put in operation anew, the end of the thread remains clamped within the jaws until the needles have seized this thread which is automatically and gradually pulled out of the jaws of the clamping device by the knitted product of increasing length being drawn away. The remaining inactive threads of the idle guides, which threads are held closely adjacent to each other between the jaws, remain at rest during this stage. The longer and shorter ends of the free threads projecting from the edges of the product before the latter have been sewn together, are subsequently trimmed by hand.

The invention is not restricted to the example described and shown and may be applied also to other working machines which operate under similar working conditions as the straight knitting frames.

What I claim is:

1. In a method of gripping and cutting off the inactive threads in straight sinker operated knitting frames and similar machines including selectively idled thread guides, the steps of au-

11

automatically pulling out the threads extending between idled thread guides and the fabric to form a V-shaped loop between the mouths of the thread guide tubes and the point of introduction of the thread into the knitted fabric, inserting 5 one of the branches of the V-shaped loops extending from the idled guides between two spring closed jaws of a clamping and cutting-off device, cutting the thread at a location close to the side of the clamping jaws, and retaining the ends of the severed threads between the jaws of the clamping device in such a way that the said severed ends do not project from the clamping jaws.

2. The method as set forth in claim 1, including 15 during the period of pulling the thread by means of one or more retaining hooks to form a V-shaped loop, moving the clamping and cutting-off device towards the loop being formed.

3. In a method of gripping and cutting off the inactive threads in straight sinker operated knitting frames and similar machines including selectively idled thread guides, the steps of automatically pulling out the threads extending between idled thread guides and the fabric to form a 20 V-shaped loop between the mouths of the thread guide tubes and the point of introduction of the thread into the knitted fabric, inserting one of the branches of the V-shaped loops extending from the idled guides between two spring closed jaws of a clamping and cutting-off device, cutting the thread at a location close to the side of the clamping jaws, retaining the ends of the severed threads between the jaws of the clamping device in such a way that the said severed ends do not project from the clamping jaws and causing the thread introducing device to be operated by the working movement of the clamping device and to be put out of operation by the return of the clamping device to its inactive position.

4. In a straight sinker operated knitting frame, an apparatus for gripping and cutting off the inactive threads comprising a pair of spring closed thread clamping jaws, one of said jaws also being provided with a cutting edge along one side thereof and a spring loaded knife mounted pivotally thereon adapted to cooperate with said cutting edge to sever the projecting portions of thread clamped between said jaws, said knife being movable with said closed clamping jaws in the direction toward a loop being formed from the inactive thread, and a pivotally mounted cam member for actuating said knife, said cam member engaging said knife to open the knife prior to entry of the thread loop between said spring-closed jaws and being thereafter released from said knife to effect closing thereof under the action of its loading spring thereby to sever the thread loop.

5. In a straight knitting frame including a knitting section comprising a needle bank, a cooperating row of sinkers and thread guides selectively operable for laying thread along the needle bank and for idling adjacent the ends thereof, a plurality of bars slidably mounted longitudinally of the frame; a thread clamping and cutting device mounted adjacent each end of the knitting section comprising a pair of spring closed clamping jaws, a thread cutting knife at one side of said jaws and a pivoted thread engaging lever for inserting threads between said jaws; a thread catching member carried by one of said bars and disposed adjacent one end of the knitting section; a thread catcher carried by another of

5 said bars and disposed adjacent the other end of the knitting section; means on a third one of said bars for actuating said thread clamping and cutting device; and means for imparting longitudinal sliding motion to said bars in timed relation to the operation of the knitting frame to shift said thread catchers into and out of the ends of the knitting section to pull out the threads between idled thread guides and the fabric and to actuate the clamping and cutting device to grip and cut the pulled out threads.

6. A knitting frame according to claim 5 in which the bars are mounted on the frame in superposed relation and a centrally located actuating member is provided for driving the bars.

7. A straight knitting frame according to claim 5 in which the frame is a multiple section frame, said bars extend across all of the sections, the thread clamping and cutting devices and thread catching members are provided at each end of each of the knitting sections, two of the bars carry all of the thread catching members and the third bar carries all of the actuating means for the respective thread clamping and cutting devices.

8. A knitting frame according to claim 7 in which all of the thread catching devices disposed at the right hand end of the respective knitting sections are carried on one of said bars and all of the thread catching devices disposed at the left hand end of the knitting sections are disposed on another bar.

9. A knitting frame according to claim 7 in which the bars are mounted in superposed relation, a cylindrical cam member is provided having driving connection with the individual bars and means are provided for driving the cylindrical cam in timed relation to drive of the knitting frame.

10. A knitting frame according to claim 9 in which the means for driving the cylindrical cam includes a coupling and drive for effecting only a single revolution of the cam with each engagement thereof and means is provided for automatically engaging said coupling upon the movement of a thread guide or thread guides to idling position at either end of the knitting section.

11. A knitting frame according to claim 10 in which the means for automatically engaging the coupling comprises a pattern drum and a lever system for actuating the coupling from the pattern drum.

12. In a straight knitting machine a needle bank and a cooperating sinker bank, a plurality 55 of automatically operated thread guides for feeding the thread to said banks and movable to idling positions adjacent the ends thereof, a thread clamping and cutting device mounted adjacent the end of the sinker bank including a 60 clamping jaw member movable transversely of the bank, a reciprocable bar mounted longitudinally of the frame, a hooked thread catcher mounted on said bar positioned normally at the end of the sinker bank and movable longitudinally into and out of the bank upon reciprocation of its carrier bar to catch a thread between an idled guide and the fabric to form a loop with the side thereof extending from the guide disposed in front of said clamping member, a pivoted 65 lever mounted on said clamping member having a thread engaging portion, means for rocking said lever to engage the last mentioned side of said loop and insert the same between the jaws of said clamping jaw member, a thread cutter mounted 70 on the side of said clamping jaw member away

from the end of the needle bank and means for actuating said cutter to sever the thread after actuation of said lever to insert the thread between the clamping jaws.

13. A method for automatically clamping and cutting off the inactive threads in a straight knitting machine having an automatically operated knitting mechanism including a needle bank and cooperating sinkers to which the thread is fed by a plurality of thread guides which are selectively moved to an idle position during the knitting of the fabric which comprises catching inactive threads between idled thread guides and the fabric by moving a thread catcher longitudinally inwardly of the end of the needle bank in timed relation to the idling of one or more of the thread guides, pulling out the threads so caught into a loop adjacent the end of the needle bank, clamping the portion of the so looped threads extending from the idled thread guides by en- 10 15 20

gaging the same between spring closed clamping jaws, cutting at the clamping jaws the threads extending between the same and the fabric so that the severed ends do not project from the clamping jaws and continuing the clamping of all of the thread ends extending from the idled guides until each is withdrawn by travel of the fabric upon return of the respective idled thread guides to operation.
